DESIGN FOR A PIE SHELL

Lloyd J. Harriss, Kenilworth, and Bernard Lamb-ers, Oak Park, Ill.; said Lambers assignor to said Harriss

Application March 27, 1941, Serial No. 99,928

Term of patent 14 years

To all whom it may concern:

Be it known that we, Lloyd J. Harriss and Bernard Lambers, citizens of the United States, residing at 110 Abington Street, Kenilworth, in the county of Cook and State of Illinois, and 1139 South Elmwood Street, Oak Park, in the county of Cook and State of Illinois, respectively, have invented a new, original, and ornamental Design for a Pie Shell, of which the following is a specification, reference being had to the accompanying drawing, forming part thereof.

In the drawing, Figure 1 is a top plan view of a pie shell showing our new design;

We claim:

The ornamental design for a pie shell, substantially as shown.
